CLAIM

The ornamental design for a pool fountain, as shown and described.

DESCRIPTION

FIG. 1 is a first perspective view of a pool fountain showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the pool fountain thereof;

FIG. 10 is a perspective view of another state of the pool fountain thereof; and,

FIG. 11 is an enlarged view of the selected portion 11 in FIG. 2.

The broken lines shown in the drawings depict portions of the pool fountain that form no part of the claimed design.
